UNITED STATES PATENT OFFICE

JACOB C. JORGENSEN, OF BEVERLY, AND NORWOOD H. KNOWLTON, OF ROCKPORT, MASSACHUSETTS, ASSIGNEES TO UNITED SHOE MACHINERY CORPORATION, OF PATERSON, NEW JERSEY, A CORPORATION OF NEW JERSEY

ASSEMBLING MACHINE

Application filed July 10, 1925. Serial No. 42,699.

This invention relates to machines for use in assembling the parts of boots and shoes upon their lasts preparatory to lasting, and particularly to devices for holding the counter portions of shoes against the rear ends of their lasts prior to and during the assembling operation. The embodiment selected for illustration is adapted to hold an upper, including an unmolded counter, against the rear end of its last as it is supported on the work support of an assembling machine preparatory to being secured to the last by the machine.

5

Objects of the invention are to render the handling of straight or unmolded counters, in the operation of assembling uppers including such counters upon their lasts, easier, more accurate and expeditious than heretofore and generally to improve the operation 10 of the assembling machine.

Features of the invention consist in an organization including a shoe support movable toward and from the machine and clamping means in the path of movement of a shoe 15 on said support arranged to hold the counter portion of the shoe upper against the last during its movement toward the machine so that there will be no chance for the parts to be displaced from the position in which they 20 have been placed by the operator. As herein shown, the clamping means is movable by pressure of the shoe against it to cause the upper to be pressed against the rear end of the last. The clamping means may be held 25 toward the shoe by resilient means, and a stop may be provided to arrest outward movement of the clamping means before the outward movement of the shoe support is completed to cause the clamp and shoe to separate. The clamping means may, as shown, 30 comprise a bar pivoted to the shoe support and bifurcated at its upper end, the bifurcations being formed with inclined surfaces which rest against the rear end of the shoe 35 upper and hold the upper and counter against the last at the corners of the last, the space between the bifurcations permitting the operation of the tacker of an assembling machine in fastening the upper and counter to 40 the last.

These and other features of the invention will appear more fully from the following description when read in connection with the accompanying drawing and will be pointed out in the appended claims.

In the drawing:

Fig. 1 is a side elevation of an assembling machine embodying the present invention;

Fig. 2 is a detail in perspective showing a shoe partly in section and parts of the mechanism shown in Fig. 1; and

Fig. 3 is a sectional view of the operating instrumentalities of the machine.

In Fig. 1 of the drawing is shown an assembling machine and a work support of the construction disclosed in United States Letters Patent No. 1,602,618, granted October 12, 1926, on application of N. H. Knowlton, in which, for the purpose of illustration, the present invention is shown as embodied. The

65 70 75

numeral 2 indicates the base of the column of the machine to which is pivoted at 4 a work support member or carrier 6. A tubular member or jack post 8 is arranged for vertical sliding movement relatively to the member 6 and is sustained in initial elevated position by a light spring 10 resting on a plug 12 which is supported on the member 6 and enters loosely the lower end of the tubular member 8. The spring at its upper end engages a pin 13 passing through the member 8 which is thus yieldingly sustained by the spring 10. In the upper portion of the member 8 is a sliding member 14 having at its upper end a heel pin 16 to engage the pin hole of the last. The member 14 is held from turning in the tube and has its vertical movement limited by a screw 17 threaded into it and engaging a slot in the tube 8. Loosely surrounding the upper end of the member 14

80 85 90 95 100

and resting on top of the member 8 is a sleeve 18 which has notches in its upper edge at different heights which are adapted to be engaged by a pin 20 in the member 14. By lifting the member 14 and turning the sleeve 18 the height of the heel pin relatively to the member 8 may be varied to accommodate lasts of widely different heights. The front face of the member 8 is provided with ratchet teeth 21 which are adapted to be engaged by

a pawl carried by a rocking member 22 pivoted to the member 6 by trunnions 23 arranged on opposite sides of the member 8. By this construction, which is more fully described in the Letters Patent above referred to, when the work support is swung toward the machine and locked against outward movement by the dropping of a hook 24 in front of a roll 25 carried on the member 6 by 10 a pin 26 the pawl referred to engages the teeth 21 and also locks the member 8 against downward movement.

When the work support is in position for the reception or removal of the shoe it is desirable that the work support be sustained against depression. For this purpose the member 8 is provided with a roll 27 which, when the support is in its extreme outward position, lies in contact with the end of a 20 curved rigid arm 28 which is fixed at its opposite end to the machine frame. When the support is in the position shown, therefore, the shoe is rigidly supported, and when the shoe is moved toward the machine the roll 27 lies over a depressed portion of the arm as shown in dotted lines and hence depression of the shoe is not interfered with.

Outward swinging movement of the shoe support is yieldingly limited by a rod 29 pivoted to the member 6.

Mechanism is provided for causing the work support to be depressed to a predetermined position as an incident to its movement toward the machine. It comprises a depressor 34 adjustably secured to the upper end of an upright bar 36 the lower end of which is slotted at 38 freely to embrace one of the trunnions 23 so that it will be moved toward the machine with the shoe support. A spring 37 is connected in an inclined position between the lower end of the bar 36 and the pin 26 on the member 6. Since the pull of the spring is in an upwardly and rearwardly inclined direction, one component of its pull tends to lift the bar and the other component tends to swing the upper end of the bar outwardly about the trunnion 23. A link 40 is pivoted at one end to the machine frame and at the other end to a stud 42 fixed in the bar 36, the link being normally in a downwardly and outwardly inclined position. The stud 42 is extended and bent inwardly to lie in the path of movement of the tubular member 8 and is preferably provided with a roll 46 to be engaged thereby. As the work support is moved inwardly the slotted lower end of the bar 36 moves with it, causing the bar to swing about the stud 42 as a fulcrum and causing mutual relative approaching movement between the presser 34 and a shoe on the last pin 16, so that by the time the member 8 engages the roll 46 the depressor 34 has assumed a position over the shoe bottom, preferably over the heel-seat portion. Further movement of the member 8 causes

the link 40 to move from the inclined position shown toward a vertical position and therefore effects a downward movement of the bar 36 and of the depressor 34, causing it to engage the shoe bottom and to depress the shoe against the spring 10 to a predetermined position.

The mechanism for clamping the counter against the last during movement of the shoe support toward the machine comprises a bar 50 pivoted at its lower end to a member 52 secured to the post 8. To the upper end of the bar 50 a clamping member 54 is attached by screws 56 which pass through vertical slots in the bar to permit adjustment of the member 54 heightwise of the last. The central portion of the upper part of the member 54 is removed to form bifurcations 57, 58 (Fig. 2) which are oppositely twisted so as to present their front faces at equal and opposite inclinations corresponding approximately to the inclination of the opposite sides of the last at the corners of the last. A spring 60 inserted between the post 8 and the bar 50 tends to hold the bar and member 54 against a pin 62 carried by a lever 64 fulcrumed at 66 to the machine frame. Beyond its fulcrum an arm of the lever 64 extends upwardly and is pivoted at 68 to a push rod 70 which extends through a conical hole 95 in a bracket 72 secured to the frame. On the rod at the rear of the bracket is an adjustable stop 74. Between the bracket 72 and an adjustable collar 78 on the rod 70 is a compression spring 76 which may be held under any desired initial tension by adjustment of the collar 78 toward the bracket 72.

In using the machine, the operator places a last *a*, having secured to its bottom an insole *b*, on the pin 16, takes an appropriate shoe upper and introduces between the lining *c* and upper leather *d* a straight or unmolded counter *e*. He then places the upper over the last with the back seam in proper position and with a suitable width of margin 110 of the upper materials extending above the bottom of the insole *b*. Then, while still grasping the last to prevent movement of the upper thereon, he pushes the shoe toward the machine. Early in its movement the rear portion of the shoe reaches the bifurcations 57, 58 of the bar 50 which engage the counter adjacent to the corners of the last and, as the motion of the shoe continues, firmly press it against the last. During this movement the clamping member 54 engages the pin 62 and moves the lever 64 rearwardly about its fulcrum 66, causing the spring 76 to be compressed and its tension applied to the clamping member 54. During further movement 125 of the shoe the pressure of the clamping member 54 is maintained and increased and the depressor 34 assumes a position over the shoe and descends to depress the shoe and the member 8 to a predetermined position. 130

The bottom of the shoe is now in the proper plane for the action of a wiper 88 and rearward movement of the shoe is arrested by engagement of the member 54 with a lower abutment or V-block 79 on the machine which has a V-shaped notch to receive the end of a shoe, the faces of the notch being preferably recessed to receive the bifurcations 57, 58 on the end of the member 54. When the shoe has almost finished its movement a collar 80 on a rod 82 connected to the member 8 engages an arm 84 and trips the clutch to start the machine, whereupon the hook 24 drops in front of the roll 25, locking the shoe against downward or outward movement while other operating instrumentalities of the machine act. A tack is driven through the abutment 79 into the rear end of the shoe, the tack passing between the bifurcations 57, 58 of the counter clamp, and a gripper 86 acts to grip the upper against the front face of the wiper 88 which moves forward to lay the projecting margin of the upper and counter upon the heel-seat when it is secured by a tack driven by a driver 90.

Having thus described our invention, what we claim as new and desire to secure by Letters Patent of the United States is:

1. In a machine of the class described, the combination of operating instrumentalities, a last support movable from a work receiving position where the work comprising an upper and last is placed thereon to a position for the work to be operated upon by said instrumentalities, and means located on the last support for clamping the upper to the last, said means being constructed and arranged to be encountered by the work early in its movement toward said instrumentalities and to be moved by the work during the remainder of its movement into operative relation to said instrumentalities, said clamping means serving to hold the upper on the last, during the movement thereof into operative relation to the operating instrumentalities, in the position in which it is placed by the operator.

2. In a machine for fastening uppers to lasts, the combination of tackling means, a last support movable from a position to receive an upper and last which is remote from said tackling means into operative relation thereto, and a clamp located adjacent to the support in its last and upper receiving position and in the path of movement of the last and upper into operative relation to the tackling means, said clamp being movable with and by the last and upper throughout the major portion of the movement of the support into operative relation to the tackling means.

3. In a machine for assembling uppers upon their lasts preparatory to lasting, the combination of upper securing means, a last support movable toward and from the securing means, counter clamping means located adjacent to the last support, means for limit-

ing outward movement of the clamping means to provide a space between the clamping means and the last to permit assembling of the upper and counter upon the supported last, said clamping means being arranged to be engaged by the rear end of the upper and last early in their movement toward the securing means to clamp the counter and upper to the last, and yielding means permitting movement of the clamp, upper and last together into operative relation to the securing means.

4. In a machine of the class described, means for inserting a tack in the rear end of a last, a last support movable from a last and upper receiving position to a position for the upper to be operated upon by said tackling means, a bifurcated member arranged adjacent to the last support in its last and upper receiving position to be encountered by the last and upper early in their movement on the support toward the tackling means for clamping an upper to the last at the corners of the last during its movement toward the tackling means, and means for locking the support against endwise movement during insertion of a tack between the bifurcations of said member.

5. In a machine for fastening uppers to lasts, the combination of a V-block, fastening inserting means operating between the V-block surfaces, a last support movable toward and from said fastening inserting means, a clamp having rear surfaces like those of the V-block and front surfaces to engage an upper and clamp it against the corners of the last having the back seam region exposed, said clamp being located between the fastening inserting means and the support in the path of the upper and last and movable with and by the upper and last when the last support is moved toward the fastening inserting means, and means for locking the last, clamp and V-block together while the fastening means inserts a tack in the region of the back seam.

6. In a machine for assembling uppers upon their lasts preparatory to lasting, the combination of fastening inserting devices for securing an upper and counter to the rear end of a last, a last support movable toward and from said devices, counter clamping means located adjacent to the support in its position away from said devices, means for limiting outward movement of the clamping means to permit assembling of the upper and counter upon the supported last, said clamping means being arranged to be engaged by the rear end of the upper and last early in their movement toward the securing devices to clamp the counter and upper to the last substantially throughout their movement toward the securing devices, yielding means permitting movement of the clamp, upper and last together into operative relation to the se-

curing devices, and means to lock the last and clamp against outward movement during operation of the securing devices.

In testimony whereof I, the said JACOB C. JORGENSEN, have signed my name to this specification.

JACOB C. JORGENSEN.

In testimony whereof I, the said NORWOOD H. KNOWLTON, have signed my name to this specification.

NORWOOD H. KNOWLTON.
